UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed October 22, 1925. Serial No. 64,147.

My invention relates to rail anchors anding the anchor in its fully applied position. 55 has for its primary object the provision of a new and improved rail anchor device which, when applied to its operative position on a rail, will maintain its operative position thereon by spring pressure and which will lock itself on the rail so as to prevent accidental removal therefrom.

Another object of the invention is to provide an improved two-piece rail anchor, in which the parts when free of the rail, are normally held together by spring pressure, so that the parts of the device may be assembled at the factory and shipped therefrom, 15 in readiness to be applied to a rail.

Another and more specific object of the invention is to provide a two-piece rail anchor in which one of the members is subjected to a torsional strain during its application to a rail, so as to exert a spring grip on the upper and lower surfaces of the rail base and is held in said torsioned condition by means of the other member, which is movable thereon and adapted to be driven into 25 engagement with the rail base.

Another object of the invention is to provide an improved two-piece rail anchor, the parts of which may be made from flat metal blanks of such configuration as to avoid any substantial loss of metal in shearing the blanks. In this connection the invention contemplates a two-piece anchor comprising a rail base embracing member formed with a recess to receive the base portion of a rail, 30 and a clip member of such shape that it may be formed from the metal removed from the recessed portion of the said rail base embracing member.

The invention has for further objects the 40 novel arrangement, construction and combination of parts hereinafter described and claimed for carrying out the above stated objects and such other objects as will appear from the following specification.

45 In the drawings:

Fig. 1 is a plan view of a rail anchor, constructed in accordance with my invention, applied to the base portion of a railroad rail.

50 Fig. 2 is a front view of the rail anchor construction shown in Fig. 1.

Fig. 3 is an end view of the anchor showing the same in its partially applied position.

Fig. 4 is a view similar to Fig. 3, but show-

Fig. 5 is a view in perspective of the two members of the improved anchor, showing the members in their normal engagement with each other when free of the rail.

Fig. 6 is a view of a metal strip showing the blanks from which the members of my improved anchor are formed, the blanks being shown in their nesting arrangement.

Fig. 7 is a view of one of the blanks shown in Fig. 6, but drawn on a larger scale, and 65

Fig. 8 is an end view of another embodiment of my invention.

Referring first to Figs. 1 to 7 inclusive of the drawings, 10 designates the base portion of a railroad rail and 11 one of the cross ties 70 on which the rail is supported. The embodiment of my invention illustrated in the above figures consists preferably of a rail base embracing yoke member 12, made of spring metal, and a clip 13 adapted to support one 75 end of the yoke in its operative position on the rail base. The body portion of the yoke is provided with a recess 14 adapted to receive the base portion of the rail, the recess being of such configuration as to provide 80 a jaw 15 at one end of the yoke and an upstanding portion 16 at the other end. The jaw 15 normally bears with spring pressure against the top surface of the rail base when the anchor is applied to its operative position, the spring pressure being effected preferably by subjecting the yoke to a torsional strain during its application to the rail.

The jaw 15 is preferably bent to an angular position with respect to the body and the body is preferably, though not necessarily, given a normal torsional set (shown best in Fig. 5) so that the end portion 16 will stand at an angle to the body of the yoke when the yoke is free of the rail. With this arrangement of the end portion 16 of the yoke with respect to the jaw 15, the end of the jaw will be forced downwardly against the top surface of the rail base when the yoke is torsioned in the direction to bring the end portion 16 to a substantially vertical position with respect to the bottom surface of the rail base.

The yoke is held in its applied torsional condition by means of the clip member 13 105 which engages the yoke and the base portion of the rail in such manner as to resist the tendency of the yoke to return to the

position from which it was sprung. The clip member consists preferably of a metal strip bent to a substantially U-shaped configuration so as to embrace the end portion 16 of the yoke. The ends of the clip are formed with recesses 17-18, which provide jaw portions adapted to be driven into tight gripping engagement with the top and bottom surfaces of the rail base at opposite sides of the yoke. One end of the clip is formed with a tongue 19 which extends into the recessed portion 14 of the yoke so as to provide an interlocking engagement of the yoke and clip when both members are in their operative position on a rail.

The clip is preferably made of spring metal and is of such shape and size that it can be formed from the metal strip removed from the recess 14 of the yoke. The form 20 of the blanks from which the yoke and the clip members are formed are shown in Fig. 6 of the drawings. By reference to Fig. 6, it will be seen that the shearing of both blanks 12^a, 13^a produces but a very small 25 amount of metal scrap, the pieces of metal scrap being indicated in said figure by reference characters A, B and C.

In producing the yoke blanks for rails having base flanges of different widths, the 30 length D of the clip blank may vary somewhat with relation to the width of the yoke and in proportion to the increase or decrease in the width of the rail base. However, when it is desired to provide the clip blank 35 with relatively heavy jaw portions 20 and 21, the length of the yoke jaw 15 may be varied to produce a longer or shorter blank, as may be desired. Under such conditions, it is also possible to obtain the desired 40 result by cutting away the lower edge of the yoke as shown at 22, in Fig. 2 of the drawings, instead of varying the length of the yoke jaw.

The clip is preferably formed so that it 45 will be necessary to spread the ends apart in applying it to the end 16 of the yoke. With such construction the clip may be fitted on the end of the yoke at the factory and shipped as a one-piece anchor, thereby avoiding 50 any misfitting of the anchor parts by the track workmen when applying the anchors.

In applying the anchor to the rail, the 55 yoke and clip, assembled, as shown in Fig. 5, are positioned on the rail base so that the jaw 15 of the yoke will be hooked over one flange of the rail base, in which position, the other end of the yoke and the clip carried thereon will stand at an angle with respect to the bottom of the rail base, as shown 60 in Fig. 3. A wrench of the type shown in outline in Figs. 1 and 3, or of other suitable form, is applied over the clip and the yoke is torsioned until the recesses 17 and 18 of 65 the clip are in line with the adjacent edge

of the rail base. The clip 13 is then driven longitudinally of the yoke 12, by striking the lower portion of the wrench with a sledge or by otherwise applying force to the clip to move the jaw portions 20, 20^a and 21, 21^a into tight gripping engagement with the upper and lower surfaces of the rail base. The tongue 19 of the clip is so proportioned with respect to the depth of the recesses 17 and 18 that it will snap back 75 of the shoulder 23 of the yoke when the clip is driven home and thereby lock the yoke and clip on the rail. The torsional strain to which the yoke is subjected during its application exerts a powerful grip of the jaw 80 15 on the rail so as to maintain the yoke in its applied position. After the clip is driven to its interlocked position on the yoke, the clip end of the anchor may be driven longitudinally of the rail to bring one face of 85 the clip into engagement with an adjacent cross tie. The other end of the yoke may be driven toward the tie until the yoke stands in a position diagonally across the rail, as shown in Fig. 1 of the drawings. In 90 the latter position the vertical shoulder 23 of the clip and shoulder 24 of the yoke take a shackle grip on opposite edges of the rail base to resist the creeping movement of the rail. The tendency which the spring yoke 95 has to return to the position from which it was sprung tends to cant the clip so as to increase the grip of its jaws on the upper and lower faces of the base flange of the rail. Ordinarily the fit of the clip jaws on the rail 100 flange will be tight enough to prevent any actual canting of the clip. However, if there is any looseness present it will be taken up by the canting action.

It will be seen from an inspection of the 105 drawings that my improved anchor may be applied to a rail with the jaw 15 in engagement with either flange of the rail base. In the arrangement shown in the drawings the jaw 15 extends toward the tie and the yoke 110 is tensioned by turning the end portion 16 thereof toward the adjacent cross tie. With this arrangement, the pressure of the clip against the tie during the presence of a creeping pressure on the rail, tends to cant the 115 clip in a direction to increase the spring grip of the jaw 15 on the upper surface of the rail base and also effect a shackle grip of the clip 120 jaws 20-21^a on the upper and lower surfaces of the rail base. When the anchor is applied 125 so that jaw 15 engages with the rail flange at the opposite side of the rail, the said jaw will extend in a direction away from the adjacent cross tie. With such arrangement the yoke will be strained to its applied position by turning the upper end 16 of the yoke in a direction away from the cross tie, that is to say, in a direction opposite to that contemplated in Figs. 3 and 4 of the drawings. Under such arrangement the pressure of the 130

clip against the tie during the presence of creeping movement of the rail will increase the canting action of the clip already effected by the tension of the spring yoke.

6 In Fig. 8 I have shown another embodiment of my invention in which the clip member is formed only with one rail base engaging recess 18^a and the clip blank so bent that the other end of the blank will 10 bear against the under surface of the rail base. With this embodiment, the clip blank may be bent at any point so that when bent in its final position it will accommodate relatively wide yoke members and thereby 15 avoid cutting away the yoke, as indicated at 22 in Fig. 2.

In the drawings I have shown my preferred form of rail embracing yoke, in which the jaw portion 15 is bent at an angle to the 20 body portion of the yoke. It will be obvious, however, that the bend in the jaw may be omitted and the jaw formed in the plane of the body.

While I have illustrated my invention 25 in two specific embodiments, it will be understood that I desire to claim the invention, both broadly and specifically in all phases coming within the scope of the appended claims.

30 I claim:

1. A rail anchor comprising a rail base embracing member adapted to engage a rail base at opposite sides of the rail and a clip 35 engaging said rail base and said embracing member, and spring means on one of said members adapted to snap into interlocking engagement with the other member.

2. A rail anchor comprising a rail base 40 embracing member adapted to engage a rail base at opposite sides of the rail and a clip engaging said rail base and said embracing member, and spring means on said clip member adapted to snap into interlocking engagement with said rail base embracing 45 member.

3. A rail anchor comprising a rail base embracing member adapted to engage a rail base at opposite sides of the rail and a clip 50 engaging said rail base and said embracing member, spring means on said clip member adapted to snap into interlocking engagement with said rail base embracing member; the arrangement of said base embracing member and said clip member being 55 such that the clip is driven transversely of the rail to its normal operative position.

4. A rail anchor comprising a spring member provided at one end with means for engaging one flange of a rail base and at the 60 other end with means for engaging the other flange of said base, and a clip slidable longitudinally of said spring member into engagement with the rail base to hold said spring member in its normal rail-gripping position.

5. A rail anchor comprising a spring member provided at one end with means for engaging one flange of a rail base and at the other end with means for engaging the other flange of said base, and a spring clip slidable longitudinally of said spring member into engagement with the rail base to hold said spring member in normal rail gripping position; the arrangement of the spring member and clip being such that the spring member is tensioned when said clip is in its normal operative position on a rail. 70 75

6. A rail anchor comprising a spring member provided at one end with means for engaging one flange of a rail base and at the 80 other end with means for engaging the other flange of said base, and a clip slidable longitudinally of said spring member into engagement with said base to hold said spring member in its normal rail gripping position; the arrangement of the spring member and clip being such that the spring member is 85 tensioned when said clip is in its normal operative position on the rail.

7. A rail anchor comprising a spring member provided at one end with means for engaging one flange of a rail base and at the other end with means for engaging the other flange of said base, and a clip slidable longitudinally of the spring member into engagement with the rail base to hold said member in its normal rail-gripping position; the arrangement of the spring member and clip being such that the spring member is required to be tensioned to permit said clip to 100 be driven to its operative engagement with the rail base. 90 95

8. A rail anchor comprising a spring member provided at one end with means for engaging one flange of a rail base and at the 105 other end with means for engaging the other flange of said base, and a clip provided with means for bearing against the top surface of a rail base at one side of the rail and slidable longitudinally of said spring member into engagement with the rail base to hold said spring member in its normal rail gripping position. 110

9. A rail anchor comprising a spring member provided at one end with means for engaging one flange of a rail base and at the other end with means for engaging the other flange of said base, and a clip provided with means for bearing against the top and bottom surfaces of the rail base at one side of the rail and slidable longitudinally of said spring into engagement with the rail base to hold said spring member in its normal rail-gripping position. 115 120

10. A rail anchor comprising a yoke member provided at one end with a jaw adapted to bear against the top surface of a rail base at one side of the rail and provided at the other end with means for engaging the rail base at the other side of the rail, and a clip 125 130

formed with portions for engaging the top and bottom surfaces of the rail base and slidable on the last mentioned end of said yoke into gripping engagement with the rail base.

11. A rail anchor comprising a yoke member formed at one end with a jaw adapted to bear against the top surface of the rail base at one side of the rail and provided at the other end with means for engaging the rail base at the other side of the rail, a clip formed with portions for engaging the top and bottom surfaces of the rail base and slidable on the last mentioned end of said yoke into gripping engagement with the rail base, and a spring tongue on said clip adapted to snap over an edge of the yoke to lock the yoke and clip in their operative position on the rail.

12. A rail anchor comprising a yoke member formed at one end with a jaw adapted to bear against the top surface of the rail base at one side of the rail and provided at the other end with means for engaging the rail base at the other side of the rail, and a spring clip embracing the last mentioned end of said yoke and provided with means for engaging the upper and lower surfaces of the rail base to support the said yoke in its gripping position; said clip being formed to maintain a spring grip on the yoke when the latter is free of the rail, but is slidable longitudinally of the yoke to effect its said engagement with the rail base.

13. A rail anchor comprising a yoke member formed at one end with a jaw adapted to bear against the top surface of the rail base at one side of the rail and provided at the other end with means for engaging the rail base at the other side of the rail, a substantially U-shaped clip embracing the last mentioned end of said yoke and provided with means for engaging the upper and lower surfaces of the rail base to support the said yoke in its gripping position and with a spring tongue adapted to snap into locking engagement with a part of the yoke when the yoke and clip are in gripping position on the rail; the ends of said clip being formed to exert spring pressure on the yoke, whereby it is retained thereon when the yoke is free of the rail, but may be slid longitudinally of the yoke to its applied rail-gripping position.

14. A rail anchor comprising a yoke member formed at one end with a jaw adapted to bear against the top surface of the rail base at one side of the rail and provided at the other end with means for engaging the rail base at the other side of the rail, and a clip normally supported on the yoke when the latter is free of the rail and adapted to be driven transversely of the rail to its normal operative position.

15. A rail anchor comprising a yoke mem-

ber formed at one end with a jaw adapted to bear against the top surface of the rail base at one side of the rail and provided at the other end with means for engaging the rail base at the other side of the rail, and a clip which normally grips the yoke with spring pressure to maintain its position thereon when the latter is free of the rail.

16. In a rail anchor, the combination of a spring yoke formed at one end with a jaw adapted to embrace the base flange of a rail at one side of the rail and provided at the other end with a portion for engaging the rail base at the opposite side of the rail, the body portion of the yoke being normally torsioned when in its operative position on the rail, whereby the said jaw is forced into gripping engagement with the rail base; and means for maintaining the yoke in its torsioned condition comprising a clip having means for engaging the rail and movable longitudinally of said yoke into gripping engagement with the rail base.

17. In a rail anchor, the combination of a spring yoke formed at one end with a jaw adapted to embrace the base flange of a rail at one side of the rail and provided at the other end with a portion for engaging the rail base at the opposite side of the rail, the body portion of the yoke being normally torsioned when in its operative position on the rail, whereby the said jaw is forced into gripping engagement with the rail base; and means for maintaining the yoke in its torsioned condition comprising a clip embracing one end of the yoke, provided with a jaw adapted to engage the rail base, and movable longitudinally of the yoke into gripping engagement with a rail base.

18. In a rail anchor, the combination of a spring yoke formed at one end with a jaw adapted to embrace the base flange of a rail at one side thereof and provided at the other end with a portion for engaging the rail base at the opposite side of the rail, the body portion of the yoke being normally torsioned when in its operative position on the rail, whereby the said jaw is forced into gripping engagement with the rail base; and means for maintaining the yoke in its torsioned condition comprising a clip arranged on one end of the yoke and adapted to be moved into gripping engagement with the rail base.

19. A rail anchor comprising a spring yoke formed at one end with a jaw adapted to embrace the base flange of a rail at one side thereof and provided at the other end with a portion for engaging the rail base at the opposite side of the rail, the body portion of the yoke being normally torsioned when in its operative position on the rail whereby the said jaw is forced into gripping engagement with the rail base, and means for maintaining the yoke in its torsioned condition comprising a U-shaped clip ar-

ranged on one end of the yoke and adapted to be moved thereon into gripping engagement with the rail base.

20. In a rail anchor, the combination of a spring yoke formed at one end with a jaw adapted to embrace the base flange of a rail at one side thereof and provided at the other end with a portion for engaging the rail base at the opposite side of the rail, the body portion of the yoke being normally torsioned when in its operative position on the rail whereby the said jaw is forced into gripping engagement with the rail base; and means for maintaining the yoke in its torsioned condition comprising a clip arranged on one end of the yoke adapted to be moved thereon into gripping engagement with the rail base, and a spring tongue on the clip adapted to snap over a part of said yoke to lock the clip thereon.

21. In a rail anchor, the combination of a spring yoke formed at one end with a jaw adapted to embrace the base flange of a rail at one side thereof and provided at the other end with a portion for engaging the rail base at the opposite side of the rail, the body portion of the yoke being normally torsioned when in its operative position on the rail, whereby the said jaw is forced into gripping engagement with the rail base; and means for maintaining the yoke in its torsioned condition comprising a U-shaped clip arranged on one end of the yoke and adapted to be moved thereon into gripping engagement with the base, and a spring tongue on the clip adapted to snap over a part of said yoke to lock the clip thereon.

22. In a rail anchor, the combination of a spring yoke formed at one end with a jaw adapted to embrace the base flange of the rail at one side thereof and provided at the other end with a portion for engaging the rail base at the opposite side of the rail, the body portion of the yoke being normally torsioned when in its applied position on the rail, whereby the said jaw is forced into gripping engagement with the rail base; and means for maintaining the yoke in its torsioned condition comprising a U-shaped clip slidale on one end of the yoke, formed with means for engaging the top and bottom surfaces of the rail base, and provided with a locking tongue adapted to snap over a part of the yoke when the clip is driven to its rail-gripping position.

23. In a rail anchor, the combination of a spring yoke formed at one end with a jaw adapted to embrace the base flange of a rail at one side thereof and provided at the other end with a portion for engaging the rail base at the opposite side of the rail, the body portion of the yoke being normally torsioned when in its operative position on the rail, whereby the said jaw is forced into gripping engagement with the rail base; and means

for maintaining the yoke in its torsioned condition comprising a U-shaped clip slidale on one end of the yoke, formed with means for engaging the top and bottom surfaces of the rail base, and provided with a locking tongue adapted to snap over a part of the yoke when the clip is driven to its rail-gripping position, the end portions of said clip being formed to exert pressure against the yoke so as to support the clip thereon when the yoke is free of the rail.

24. In a rail anchor, the combination of a spring yoke formed at one end with a jaw adapted to embrace the base flange of the rail at one side thereof and provided at the other end with a portion for engaging the rail base at the opposite side of the rail, the body portion of the yoke being normally torsioned when in its operative position on the rail, whereby the said jaw is forced into gripping engagement with the rail base; and means for maintaining the yoke in its torsioned condition comprising a U-shaped clip slidale on one end of the yoke, formed with means for engaging the top and bottom surfaces of the rail base, and provided with means adapted to snap over a part of the yoke when the clip is driven to its rail gripping position, the arrangement of said yoke and clip being such that the torsional stress of the yoke is exerted through said clip against the upper and lower surfaces of the rail base.

25. In a rail anchor, the combination of a spring yoke formed at one end with a jaw adapted to embrace the base flange of a rail at one side thereof and provided at the other end with a portion for engaging the rail base at the opposite side of the rail, the body portion of the yoke being normally torsioned when in its operative position on the rail, whereby the said jaw is forced into gripping engagement with the rail base; and means for maintaining the yoke in its torsioned condition comprising a U-shaped clip slidale on one end of the yoke, formed with means for engaging the rail base on opposite sides of the yoke, and provided with a locking tongue adapted to snap over a part of the yoke when the clip is driven to its rail-gripping position.

26. In a rail anchor, the combination of a spring yoke formed at one end with a jaw adapted to embrace the base flange of a rail at one side thereof and provided at the other end with a portion for engaging the rail base at the opposite side of the rail, the body portion of the yoke being normally torsioned when in its operative position on the rail, whereby the said jaw is forced into gripping engagement with the rail base; and means for maintaining the yoke in its torsioned condition comprising a U-shaped clip slidale on one end of the yoke formed with rail base receiving recesses on opposite sides

of the yoke, and provided with a locking tongue adapted to snap over a part of the yoke when the clip is driven to its rail-gripping position.

27. In a rail anchor, the combination of a spring yoke formed at one end with a jaw adapted to embrace the base flange of the rail at one side thereof and provided at the other end with a portion for engaging the rail base at the opposite side of the rail, the body portion of the yoke being normally torsioned when in its operative position on the rail, whereby the said jaw is forced into gripping engagement with the rail base; and means for maintaining the yoke in its torsioned condition comprising a U-shaped clip slidable on one end of the yoke, provided with rail gripping means, and provided with a tie-abutting portion whereby the yoke may assume a position diagonally across the rail base to effect a shackle hold on opposite edges of the rail base.

28. A rail anchor comprising a yoke member formed from a blank sheared along lines to provide a recess to receive the base portion of a rail, and a clip member adapted to support one end of the yoke member formed from a metal blank, the length and width of which are substantially equal to the length and width of the strip of metal removed from the recess of said yoke blank.

29. A rail anchor comprising a yoke member formed from a blank sheared along lines to provide a recess to receive the base portion of a rail, and a substantially U-shaped clip member adapted to embrace one end of the yoke and being formed from a blank, the length and thickness of which are substantially equal to the length and thickness of the metal strip removed from the recess of said yoke blank.

30. A rail anchor comprising a yoke member formed from a blank sheared along lines to provide a recess to receive the base portion of a rail, and a clip member adapted to support one end of the yoke formed from a metal blank provided at one end with a recess adapted to fit over one edge of a rail base and bent to bear at the other end against the bottom surface of the rail base.

31. A rail anchor comprising a yoke member formed from a blank sheared along lines to provide a recess to receive a base portion of a rail, and a clip member adapted to support one end of the yoke, said clip member being provided at one extremity with a spring tongue and bent to bear at the other extremity against the bottom surface of the rail.

32. A rail anchor comprising a spring bar recessed to form at one end a rail gripping jaw portion adapted to bear with spring pressure against the top surface of the rail base and provided at the other end with a jaw portion adapted to be driven transverse-

ly of the rail into gripping engagement with the top and bottom surfaces of the rail base, the said bar being formed with a normal torsional set, whereby said jaw portions are normally disposed at an angle to each other 70 when the device is free of the rail and whereby it is necessary to subject said bar to torsional stress when moving the second mentioned jaw into position to engage the rail base.

33. A rail anchor comprising a spring bar recessed to form a rail gripping jaw portion at one end thereof adapted to bear with spring pressure upon the top surface of the rail base at one side of the rail and provided at the other end with a jaw portion adapted to be driven transversely of the rail into gripping engagement with the top and bottom surfaces of the rail base at the other side of the rail, said bar being formed with a normal torsional set whereby said jaw portions are normally disposed at an angle to each other when the device is free of the rail and whereby it is necessary to subject said bar to torsional stress in moving the second mentioned jaw portion into position to engage the rail base.

34. A rail anchor comprising a yoke member formed at one end with a jaw adapted to bear against the top surface of one base flange of the rail, a clip slidably engaging the other end of said yoke and provided with jaws for engaging the top and bottom surfaces of the other base flange of the rail, said clip jaws being disposed with relation to said yoke jaw, whereby the yoke is torsioned when moving said clip jaws into position to bear against the top and bottom surfaces of said base flange.

35. A rail anchor comprising a yoke member formed at one end with a jaw adapted to bear against the top surface of one base flange of the rail, a clip slidably engaging the other end of said yoke and provided with jaws for engaging the top and bottom surfaces of the other base flange of the rail, said clip jaws being disposed with relation to said yoke jaw, whereby the yoke is torsioned when moving said clip jaws into position to bear against the top and bottom surfaces of said base flange and whereby pressure of the clip against a cross tie tends to increase said torsion of the yoke.

36. A rail anchor comprising a yoke member formed at one end with a jaw adapted to bear against the top surface of one base flange of the rail, a clip movable into interlocking engagement with the other end of said yoke, and provided with jaws for engaging the top and bottom surfaces of the other base flange of the rail, said clip jaws being disposed with relation to said yoke jaw whereby the yoke is torsioned when moving said clip jaws into position to bear against the top and bottom surfaces of said

base flange, and whereby pressure of the clip against a cross tie tends to increase said torsion of the yoke.

37. A rail anchor comprising a spring yoke member formed at one end with a jaw adapted to bear against the top surface of one base flange of the rail, a clip slidably engaging the other end of said yoke and provided with jaws for engaging the top and

bottom surfaces of the other base flange of

the rail, said clip jaws being disposed with relation to said yoke jaw, whereby the yoke is torsioned when moving said clip jaws into position to bear against the top and bottom surfaces of said base flange, so that the tension of said yoke tends to cant the clip to effect a shackle hold on the rail base, and whereby pressure of the clip against the tie tends to increase said shackle grip. ¹⁵
